United States Patent Office

Des. 181,313
Patented Oct. 29, 1957

181,313

ROTOR SLEIGH

Gerald M. Reed, Los Angeles, Calif.

Application August 8, 1955, Serial No. 37,362

Term of patent 14 years

(Cl. D14—24)

FIG. 1.

FIG. 2.

FIG. 3.

FIG. 4.

Fig. 1 is a side elevational view of a rotor sleigh showing my new design;

Fig. 2 is a plan view thereof;

Fig. 3 is a front elevational view thereof; and

Fig. 4 is a rear elevational view thereof.

I claim:

The ornamental design for a rotor sleigh, substantially as shown.
